DENTAL FLOSS HOLDER

Arthur L. Peterson, Long Beach, Calif.

Application June 20, 1938, Serial No. 214,671

9 Claims. (Cl. 132—92)

This invention is a dental floss holder.

It is now a more or less general practice to not only frequently clean the teeth of the mouth with various forms of tooth brushes, but the further care of the teeth is greatly advanced by the reciprocation of a string of dental floss between the teeth to keep them clear of each other and eliminate accumulation of deposits which gender decay.

10 It is an object of the present invention to greatly increase and encourage the more general use of floss by the people for tooth preservation by the provision of a simple, practical, low-cost, easily operated and substantial floss holder and applicator. A further object is to provide a floss holder which may be readily incorporated in conventional tooth brush structures in original manufacture, or may be readily applied to various forms in finished state and in general use.

20 Also, an object of the invention is to provide a floss holder readily adjustable as to its manipulating handle to facilitate access to either front, side or back teeth of the user.

An additional object is to provide a floss holder 25 of few and simple parts and which provides for ready interchange of refill floss rolls as necessary from time to time.

The invention consists in certain advancements in this art as set forth in the ensuing disclosure and having, with the above, additional objects and advantages as hereinafter developed, and whose construction, combinations and details of means will be made manifest in the description of the manner of operation and of the herewith illustrative embodiment; it being understood that modifications, variations and adaptations may be resorted to within the scope, spirit and principle of the invention as it is more directly claimed hereinbelow.

40 Figure 1 is a side elevation of a tooth brush and an attached floss holder of this invention, and Figure 2 is an end elevation thereof.

Figure 3 is a plan of the holder as adjusted along, that is, set in a longitudinal position on the brush handle, and Figure 4 is a plan showing the holder turned to a transverse position on the handle, with parts in axial section.

Figure 5 is a sectional elevation or side view of the unloaded floss roll.

50 Figure 6 is a sectional detail of the floss cutter mounting and its setting spring.

Fig. 7 is a sectional detail of a modified form of floss clamp.

The holder assembly includes a floss receiving 55 roll 2 with an inner end flange 3 and an outer

end or cap disc 4 inwardly of which projects a short conical flange 5. A considerable length of floss F may be wound on the roll 2 between its flange and its head. This roll 2, when filled, is adapted to be readily inserted endwise into a 5 complementary barrel 6 having a closed bottom 7 and the front or open end of which is conically bored at 8 to very snugly receive and frictionally bind on the inserted conical part 5 of the roll 2 so the inserted roll will remain in place and 10 not turn when the floss is in use.

The barrel 6 is fixed at one side to the tangentially extending mounting shank 10 from whose opposite end there upstands a prong 11 with a floss notch 12 in its end to receive a length 15 of the floss F drawn through a small hole 13 in the upper part of the barrel 6 and at about the level of the notch in the end of the prong 11; the barrel and the shank, with its prong all preferably being of integral structure and of any 20 suitable material, particularly Celluloid, or other tough composition.

By slightly loosening the roll 2 in the barrel 6 the floss can be unrolled and drawn to the prong 11 thence down the outside thereof to and wound, 25 one or two times, around the stem 15 of a clamp and cutting head 16 when the stem is depressed in an aperture 18 therefor passing through the bend of the prong 11 where it joins the shank 10. The stem 15 is non-rotatively mounted in the 30 aperture 18 so that when the end of the floss is snapped into a cutting notch 17 in one side of the head 16 the used, drawn-off end of the floss may be easily cut and discarded. The head is normally retracted to cutting position by a small, 35 stiff spring 19 mounted on the stem 15 under a rear end shoulder 20 of the stem.

It will be understood that the barrel 6 and the prong 11 may be formed as an original part of a tooth brush handle H if so desired.

40 In the present disclosure the shank 10 is provided with a means for removably attaching it to the handle H and for enabling it to be adjusted to any desired transverse or parallel position.

The attaching means includes a bifurcated 45 loop or clamp 21 forming yieldable side arms 22 to slidably and adaptably receive brush handles of various cross-sectional form. As here shown the tips of the arms curve inwardly out of plane so that they may bind at the points on an in- 50 serted handle H.

To provide for transverse or other angular adjustment of the shank 10 as to its support, it is joined thereto by a journaling rivet 23, with ample friction to hold it at desired adjustment. 55

A modified form of floss clamp is shown in Fig. 7 as including a leaf spring 25 having its forward end passed through a hole 27 in prong 11, and provided with a downturned clamping bill 26 to bind on the tail end of the floss.

5 What is claimed is:

1. The combination with a handle, of a dental floss holder having means for pivotal adjustment of the holder on the handle to dispose the floss 10 strand at desired angle to or parallel therewith and including a base attachable to the handle, and a mounting pivotally fixed on the base for application as a unit.

2. A handle provided with a floss stretching 15 holder, and means for pivotally connecting the holder to the handle for longitudinal and transverse arrangement of a tensioned strand of the floss and including an attaching base having frictional grip arms and a pivot for said holder.

20 3. A combined dental floss holder and strand tensioning means, and means for frictionally and slidably attaching it as a unified assembly to the conventional tooth brush handle without change thereof in any manner and having a pivot for 25 the first-named means.

4. The device of claim 3, and said attaching means including a handle receiving, clip on clamp with compensating, cylindric grip arms.

5. A dental floss device including a barrel and 30 a strand supporting prong connected thereto in laterally spaced relation, and means for holding

a tensioned strand extending between the barrel and said prong and including a rotative barrel part carrying floss and frictionally held in the barrel, and a cooperative yieldable clamp.

6. A dental floss holder including a barrel having a floss pass hole in one side, and a floss holding roll forming a side of and restrainingly fitted in the barrel and rotative to feed off the floss to the said hole, and means to receive and support the issued strand of floss and place it under tension while the roll is held stationary in the barrel, said means including a binder for the tail end of the strand.

7. The holder of claim 6, the barrel and the roll having directly engaging, frictional binding 15 surfaces whereby to tension the strand.

8. A tooth applicating, floss holding device including a barrel having a tangentially projected shank with an upstanding prong on the same side as the barrel, and means including a floss 20 reeling roll forming a closure for and normally fitted and held against rotation in the barrel, and a tail end clamp for tensioning the floss strand between the barrel roll and the prong.

9. The device of the class described, provided 25 with a resilient clip-on device having a top basal part and thickness compensating spring arms for frictionally attaching the holding device to a conventional tooth brush handle.

ARTHUR L. PETERSON.
